John D. Davis.

UNITED STATES PATENT OFFICE.

IRA CHURCH, OF MUSKEGON, MICHIGAN, ASSIGNOR OF ONE-HALF TO LOTTIE SANFORD,
OF REED CITY, MICHIGAN.

WRENCH.

1,326,391.

Specification of Letters Patent. Patented Dec. 30, 1919.

Application filed March 13, 1919. Serial No. 282,417.

To all whom it may concern:

Be it known that I, IRA CHURCH, a citizen of the United States, residing at Muskegon, in the county of Muskegon and State of Michigan, have invented new and useful Improvements in Wrenches, of which the following is a specification.

The present invention relates to wrenches and its object is generally to provide an improved implement of that character; and more particularly, to provide a wrench whose parts may be so adjusted as to turn the work—as a nut or a bolt—readily and very quickly, and when greater resistance to the action of the wrench is encountered, whose parts may be otherwise so adjusted as to turn the work with more power.

This and any other objects hereinafter appearing are attained by, and the invention 20 finds preferable embodiment in, the structure hereinafter described and illustrated by the accompanying drawings, in which:—

Figure 1 is a top plan view of a wrench;

Fig. 2 is a side view of the same, certain 25 parts being broken away;

Fig. 3 is a sectional view of parts taken on a plane corresponding to line 3—3 of Fig. 2;

Fig. 4 is a detail view, partly in longitudinal central section, of the work-engaging 30 member of the wrench; and.

Figs. 5 and 6 are views in perspective of certain attachable parts thereof.

In the embodiment of the invention chosen for illustration by the drawings and 35 for detailed description in the body of this specification, the wrench has a body portion 1 which carries a rotatable work-engaging member 2 having the spindle 3 which may be secured in its rotary bearing 4 in the body 40 as by a pin 5 engaging the annular groove 6 in the spindle, as shown in Fig. 3.

The body carries also a handle 7 in non-rotatable and splined relation to its spindle 8, the radial pin 9 of the handle passing 45 through the elongated slot 10 of the spindle, so that the handle may slide axially on the spindle but is non-turnable in relation to it. The handle's spindle 8 rotates in the bearing 11 in the body.

50 Suitable means for rotating the work-engaging member 2 by the rotation of the handle are provided, being in the construction shown, the bevel gear 12 in keyed relation to said member 2 and the meshing bevel gear 13 in keyed relation to the handle's

spindle 8. Means for locking the handle and thereby the work-holding member against rotation are also provided, being in the construction illustrated, the clutch-member 14 at the end of the body and the co-operating clutch-member 15 at the inner end of the handle.

The socket 16 sunk in the end of the work-engaging member 2 receives the work (as the bolt or nut) to be turned by the wrench. 65 Various devices may be adopted to fit the tool for nuts and bolts of different sizes and shapes, as the attachments 17 shown in Fig. 5 and 18 shown in Fig. 6, the first having a hexagonal socket 19 and the other a square 70 socket 20, and each having a shank 21 adapted to fit in the socket 16 in the member 2 itself.

The wrench may be operated in the following manner: The work being inserted 75 into the socket 16 (or into the socket 19 or 20 in case the device shown in Figs. 5 or 6 is employed), the handle 7 is slid toward the body 1 so as to move the clutch members 14, 15 into mutual engagement. Such engagement holds the handle and thereby the work-engaging member 2 against rotation through the meshing of the gears. Great power is exercised on the work in this adjustment, the length of the lever exerting 80 the wrenching operation extending from the axis of the work-holding member to the grasped handle. A very tightly screwed down nut may be thus loosened and slowly turned. If the arc through which the lever 85 can swing be limited, the handle may be slid back to the position shown in Figs. 1 and 2, whereupon it may freely rotate while the wrench is swung to original position, the work remaining stationary during this 90 movement: the handle being now slid to engage the clutch members, the wrench may be again swung, whereby the nut is given another loosening turn. When the nut is loosened sufficiently to turn comparatively 95 easily, it may be readily and rapidly turned by holding the body of the wrench stationary and rotating the handle, the clutch members being out of mutual engagement 100 as shown in Figs. 1 and 2.

A similar operation but reversed in order of procedure may be employed to turn the nut onto its bolt, and it will be seen that such operation may be conveniently carried out, for the sockets will hold the nut with- 110

out the necessity of using the hands for that purpose. This wrench may be employed in many difficult positions, as in tightening or loosening the nuts which hold the removable member of the box containing the crank pin of an automobile engine.

The invention being intended to be pointed out in the claims, is not to be limited to or by details of construction shown or 10 described.

I claim:

1. In a wrench; a body; a rotatable work-engaging member carried by the body; a rotatable handle carried by the body; means 15 for rotating said member by the rotation of the handle; means for holdingly engaging the handle directly and thereby locking the same and said member against rotation.
2. In a wrench; a body having a clutch- 20 member; a rotatable work-engaging member carried by the body; a rotatable handle car-

ried by the body, and having a clutch member, and being slidably axially into and out of the mutually engaging position of the clutch members; means for rotating the 25 work-engaging member by the rotation of the handle.

3. In a wrench; a body having a clutch-member; a rotatable work-engaging member carried by the body and having a gear; a 30 rotatable handle carried by the body and having a gear meshing with the first-mentioned gear, a portion of the handle being in splined relation with the second-mentioned gear, and having a clutch member, 35 and being slidably axially into and out of the mutually engaging position of the clutch members.

In testimony whereof I have hereunto set my hand at Grand Rapids, Michigan, 40 this 8th day of March, 1919.

IRA CHURCH.
